N° 1100.
DES.

George Blanchard, manufacturer, N.Y.
Design for Hatch guard.
Patented May 10, 1859.

Serial 5104859

George Blanchard, manufacturer of Fire Engine Hose
Hudson, 607½ Broadway, N.Y.
H. W. Spruce, 13 Spruce St., N.Y.

George Blanchard

Des. 1100

George Blanchard, of New York, N.Y.
Letters Patent No. 1100, dated May 11, 1859.

The schedule referred to in these Letters Patent and making part of the same.

To all whom it may concern:

Be it known that George Blanchard, of the City and County

2

Des. 1100

of New York and State of New York, have invented or produced a new and original design for Watch Guards, and I do hereby declare that the following is a full and exact description of the same. Refer to Drawing.

Description.

The Watch Guard may be made of Leather or any other suitable material Riveted together or made to imitate Riveting so as to Represent a common water or fire engine hose as may be seen in the accompanying drawings.

What I claim and desire to secure by Letters Patent is making a Watch Guard to Represent a fire engine hose & pipe as Represented in the accompanying drawings.
